United States Patent Office

Des. 203,010
Patented Nov. 23, 1965

203,010

JUG HOLDER

Edward B. Graham, 7212 Sunset Ave., and Harry E. Wall,
5758 Hoffman Lane, both of Fair Oaks, Calif.

Filed July 17, 1964, Ser. No. 80,914

Term of patent 14 years

(Cl. D58—26)

FIG. 1.

FIG. 2.

FIG. 3.

FIG. 4.

FIG. 5.

We claim:

The ornamental design for a jug holder, as shown.
